UNITED STATES PATENT OFFICE.

CHARLES W. HUBBARD, OF WESTON, MASSACHUSETTS.

TWISTING AND WINDING APPARATUS.

1,258,412.

Specification of Letters Patent.

Patented Mar. 5, 1918.

Application filed June 27, 1916. Serial No. 106,246.

To all whom it may concern:

Be it known that I, CHARLES W. HUBBARD, a citizen of the United States, residing at Weston, county of Middlesex, State of Massachusetts, have invented an Improvement in Twisting and Winding Apparatus, of which the following description, in connection with the accompanying drawing, is a specification, like characters on the drawing representing like parts.

This invention relates to apparatus for twisting and winding yarn of the type illustrated in my co-pending application Ser. No. 25,386, filed May 3, 1915, and in my Patent No. 1,232,686, dated July 19, 1917, and which comprises a rotatable yarn receiver and a winding head constructed to build up in the yarn receiver a yarn mass in layers extending transversely to the axis of rotation.

20 The objects of the present invention are to provide a simplified apparatus of this type which is capable of high speed operation; to provide an improved means for producing the requisite relative rotary movement between the winding head and the yarn receiver; to provide an apparatus in which such requisite relative movement is derived entirely from the rotative movement of the driving member for the yarn receiver so that the apparatus can be operated from a single driving element, and otherwise to improve devices of this nature, all as will be more fully hereinafter set forth and then pointed out in the appended claims.

35 In order to give an understanding of my invention, I have illustrated in the drawings some selected embodiments thereof which will now be described.

Figure 1 is a vertical sectional view of 40 an apparatus embodying my invention;

Fig. 2 is a sectional view on the line 2—2, Fig. 1;

Fig. 3 is an enlarged sectional view on the line 3—3, Fig. 1;

45 Fig. 4 is a detail view of the differential gearing by which the relative rotation between the winding head and the yarn receiver is secured;

Fig. 5 is an enlarged section on the line 50 5—5, Fig. 1;

Fig. 6 is a view similar to Fig. 5 but showing a modified form of the invention.

I have shown at 1 a yarn receiver of the type illustrated in my above-mentioned application and patent, it having an elongated tubular form. Situated within the yarn receiver is a yarn support 2 on which the yarn mass 3 is built up, said yarn support being slidable longitudinally of the yarn receiver as the yarn mass 3 accumulates. This yarn support is constructed to have frictional engagement with the walls of the yarn receiver, and for this purpose is provided with two friction members 4 which engage the walls of the yarn receiver and which are 65 yieldingly held against said walls by a spring or springs 5. This form of yarn receiver support is similar to that illustrated in my Patent No. 1,232,686, above referred to.

The yarn receiver 1 is detachably secured 70 at its upper end to and is sustained by a driving member 6 by which it is rotated. At its lower end the yarn receiver has engagement with a step bearing which serves to hold said lower end of the yarn receiver in 75 proper axial position as it is rotated by the driving member. The step bearing herein illustrated comprises a spindle 7 rotatably mounted in a bearing sleeve 8 and sustained on a step 9. The upper end of the spindle 80 is provided with a nose or projection 10 which enters a central aperture in the bottom 11 of the yarn receiver. Said spindle is also provided with a flange 12 having a projection 13 which enters a notch or recess 14 formed in said bottom 11. The bearing member 8 is received in a holder 15 which is slidable vertically in a standard or support 16, said holder being keyed or splined to the standard, as shown at 17. 90 The purpose of making the holder 15 with the step bearing therein vertically movable in the standard 16 is to provide for lowering the bearing so as to detach it from the yarn receiver when the latter is to be removed 95 from the machine. The holder 15 is engaged by a resilient arm 18, the resiliency of which normally presses the holder 15 upwardly and which preferably has sufficient resiliency to retain the holder in its elevated 100

position even when the yarn receiver is supported thereon. The arm 18 is provided with an extension 19 forming a foot piece adapted to be engaged by the foot of the 5 operator so that when the operator depresses the arm 14, the holder 15 may be lowered thereby to disengage the bearing from the yarn receiver 1. I have provided herein means for positively locking the holder 15 10 in its elevated or operative position, this locking means being in the form of a locking bar 20 slidably mounted in the standard 16 and adapted to engage a groove 21 formed in one side of the holder 15. The locking 15 bar 20 is provided with the recessed portion 22 which is so shaped that when the locking bar is moved into a position to bring said recessed portion opposite the holder 15, then said holder can be moved vertically. When 20 the locking bar is in the position shown in Fig. 2, however, the holder will be positively locked in its elevated position.

As stated above, the upper end of the 25 yarn receiver is detachably connected to a driving member 6 which is rotatably mounted on a hollow shaft 23 that is sustained in a suitable bearing 24. This driving member 6 is constructed to present the belt-receiving portion 25 about which the driving pulley 30 passes and the bell-shaped extension 26 which incloses the winding head, presently to be described, and to the lower end of which the yarn receiver 1 is secured. The 35 yarn receiver is shown as having an extension 27 at its upper end which is detachably secured to the lower end of the bell-shaped extension 26 by a bayonet lock joint, as shown at 28.

The winding head by which the yarn 40 mass 3 is built up in layers extending transversely to the axis of rotation is in some respects similar to that shown in my above-mentioned co-pending application and patent in that it comprises a winding plate 45 29 resting on the yarn mass and provided with a yarn-delivery slot 30, extending substantially radially thereof, and a yarn guide 31 which is caused to vibrate longitudinally of the slot, and in that it also is provided 50 with means to cause the winding plate and yarn receiver to have a relative rotary movement thereby to provide for the winding action. The rotation of the yarn receiver provides for the twisting of the yarn and 55 the relative rotation between the yarn receiver and winding plate determines the speed of winding movement.

This winding plate 29 is secured to the lower end of posts 32 depending from a 60 head 33 inclosed within the extension 26, said head being rotatably mounted on the lower end of the hollow spindle 44 which extends up through the hollow shaft 23. The yarn guide 31 is constructed and actuated 65 somewhat similar to the corresponding

element of my above-mentioned Patent No. 1,232,686. Said yarn guide is formed on the end of an arm 34 which depends from a rock shaft 35 journalled in bearings 36 formed in the head 33. This rock shaft is 70 provided with a projection 37 having a roll 38 thereon which operates in a cam groove 39 formed in a cam element 40 rotatably mounted on a stud 41 and carried by the head 33. The rotation of the cam 40 will 75 thus give the yarn guide 31 its requisite vibrating movement. The mechanism for thus rotating the cam 40 will be presently described.

The device herein shown also includes a 80 vibrating compensating arm 42 having a guide eye 43 through which the yarn 85 passes prior to its passage to the yarn guide 31, all as shown in my above-mentioned patent. The yarn 90 is delivered to the eye 43 of the compensating member 42 through the hollow spindle 44 that extends axially through the shaft 23. This compensating member co-acts with the yarn guide 31 to draw surplus yarn through the spindle 44 95 when the yarn guide is swinging toward the center, and is thus delivering yarn at a decreasing speed, and to give up said surplus yarn when the yarn guide is moving toward the circumference and is thus delivering yarn at a progressively-increasing speed, the result being a uniform delivery 100 of yarn through the spindle 44.

The means herein shown for operating the compensating arm 42 is somewhat similar to that illustrated in my above-mentioned patent. Said compensating member is secured to a rock shaft 45 journalled in a bearing 46 formed in the head 33, and said rock shaft is provided with a projection 47 having a roll 48 operating in a cam groove 49 formed in a cam 50 which is rotatably mounted on a stud 51 carried by the head 33. I have provided herein a simplified mechanism for giving the head 33 and winding plate 29 a rotative movement relative to the rotative movement of the yarn receiver, which mechanism is actuated entirely from the rotative movement of the driving member 6. The shaft 23 is provided at its 110 lower end with a worm 52 meshing with a worm gear 53 fast on a horizontally-extending shaft 54 that is journalled in bearings 55 carried by a sleeve 56 which is rigid with and consequently rotates with the driving 115 member 6. The worm gear 53, therefore, is carried bodily around the axis of the shaft 23 with the driving member 6. Assuming that the shaft 23 is stationary and non-rotative, it will be seen that the bodily 120 rotative movement of the worm gear 53 about the shaft 23 will cause the worm 52 to rotate on its own axis as it revolves about the shaft 23. This rotation of the worm gear 53 about its own axis is made use of to 125 130

produce the necessary relative movement between the head 33 with its winding plate 29 and the yarn receiver.

In the construction shown in Figs. 1 to 5 inclusive, the worm gear 53 has rigid therewith a beveled gear 60 which meshes with a bevel gear 57 journaled on a stud 58 carried by the lower end 59 of the sleeve 56. This bevel gear 57 has rigid therewith a spur gear 61 meshing with a gear 62 which is rigid with the head 33. The gear 62 is shown as keyed to a hub 63 which is rigid with the head 33. With this construction it will be seen that the bevel gear 60 partakes of the rotative movement of the worm gear 53 and this rotative movement is communicated through the bevel gear 57 and gears 61 and 62 to the head 33 so that said head and the winding plate 29 are given a rotative movement relative to the yarn receiver 1. This relative movement is thus derived from the rotative movement of the driving member 6, thus obviating the necessity of a separate drive for the winding head.

The rotative movement of the cams 40 and 50 is also secured from this relative movement of the winding head and driving member 6. The sleeve 56 is provided with an extension 64 which depends into the head 33 and is connected to a gear 65 situated co-axially with the shaft 23 and loosely mounted on a sleeve 66 rigid with the head 33. This gear may be connected to the extension 64 in any suitable way, but I have herein shown for this purpose a detachable connection comprising a finger or projection 67 extending from the hub of the gear 65 and engaging a notch 68 formed in the lower end of the extension 64. This gear 65 meshes with two gears 69 and 70 that are rigid with the cams 40 and 50, respectively. The gear 65 will thus rotate with the driving member 6 and the relative rotary movement between the driving member and the winding head will give rotative movement to the gears 69 and 70 and thus rotate the cams 40 and 50 about their own axes as the winding head rotates about its axis. The gearing mechanism by which the winding head is given a movement relative to the driving member and by which the cams 40 and 50 are rotated is compact and is simple in construction. Moreover, it has the advantage that it is operated entirely by the rotative movement of the driving member 6, thus making a self-contained mechanism.

The head 33 is provided with the upwardly-extending annular flange 71 which incloses the gearing above referred to, thus making a gearing casing in which lubricant may be placed so that the gears may be thoroughly lubricated.

I have also provided means for varying the rotative movement between the driving

member with its attached yarn receiver and the winding head thereby to vary the amount of twist put into the yarn and the speed at which the yarn is wound. I accomplish this herein by providing means for rotating the shaft 23 in one direction or the other. If the shaft 23 is stationary and the yarn receiver is rotating at a predetermined speed, then the winding head and yarn receiver will have a predetermined movement relative to each other. If with the same speed of rotation of the driving member 6 the shaft 23 is rotated in one direction, then the relative movement between the driving member and the winding head will be increased, while if said shaft is rotated in the opposite direction, this relative movement will be decreased. By thus rotating the shaft 23 at different speeds, any desired relative movement between the yarn receiver 1 and the winding head can be secured. For thus rotating the shaft 23, I have herein shown a worm 72 formed on a sleeve 73 which is fast to the shaft 23, but is held from movement longitudinally of said shaft by the bearing 24. This worm 72 meshes with and is driven by a worm gear 75 on a shaft 74. The shaft 74 may be rotated by any suitable means adapted to give said shaft rotation in either one direction or the other at any desired speed. When the shaft 74 is at rest, then the gear 72 and the shaft 23 will be held stationary, but by rotating the shaft 74 in one direction or the other, the shaft 23 may be rotated in one direction or the other thereby to vary the relative movement between the yarn receiver and the winding head.

In Fig. 6 I have shown a slightly different arrangement of differential gearing for producing the relative rotary movement between the winding head and the yarn receiver. In this embodiment the worm gear 53 which meshes with the worm 52 is fast on a shaft 54 which has a spur gear 80 thereon. Said gear 80 meshes with a pinion 81 on a shaft 82 which is suitably journaled in a bearing formed in the portion 59 of the sleeve 56. This shaft 82 has a beveled gear 83 thereon which meshes with a bevel gear 84 integral with the gear 62 that is rigid with the winding head. The operation of the gearing shown in Fig. 6 is similar to that shown in Figs. 3, 4 and 5, the principal difference between the two differential gears being in the location of the bevel gears.

In order to prevent the yarn from wearing the guide eye 31 of the yarn guide, I have made said eye somewhat elongated, as best seen in Fig. 3, and have arranged the yarn-delivery slot 30 at a slight inclination as will also be seen from Fig. 3. This inclination of the slot will cause the yarn to have a back-and-forth traverse longitudinally of the guide eye 31 as said yarn guide vibrates.

and the wear of the yarn on the guide eye will thus be evenly distributed throughout the length thereof. This construction obviates the possibility of the yarn wearing a 5 groove in the guide eye, as sometimes occurs where the yarn has no traverse in said eye. It will be seen from the above that the mechanism illustrated is comparatively simple and that it has the advantage that only one 10 driving element is necessary, that being the driving element 6 for the yarn receiver, the relative rotary movement between the yarn receiver and winding head being produced by differential gearing which is actuated by 15 the rotary movement of the driving member. Further, this gearing is entirely inclosed and can, therefore, be operated in oil or other lubricant. The device has the further advantage that it can be run at a very high 20 rate of speed without producing any appreciable jar or vibration or noise.

I claim:

1. In an apparatus for twisting and winding yarn, the combination with a rotatable 25 yarn receiver, of a driving member therefor situated co-axially therewith and connected directly thereto, a winding head constructed to wind a yarn mass in said yarn receiver under pressure and in layers extending transversely to the axis of rotation of the yarn receiver, and means operated by the rotary movement of the driving member to cause a relative rotary movement between the winding head and yarn receiver.
- 30 2. In an apparatus for winding and twisting yarn, the combination with a rotatable yarn receiver, of a driving member therefor situated axially thereof and connected directly thereto, a winding head constructed to wind a yarn mass in said yarn receiver in layers extending transversely to the axis of rotation of the yarn receiver, and means operated by the rotary movement of the driving member to rotate the winding head at a 45 different rate of speed than that of the yarn receiver.
- 35 3. In a device of the class described, the combination with a rotatable yarn receiver, of a driving member therefor situated co-axially therewith and connected directly thereto, a winding head comprising a winding plate and a yarn guide, and means operated by the rotary movement of the driving member to cause relative rotary movement 50 between the yarn receiver and winding head and to vibrate the yarn guide.
- 40 4. In a device of the class described, the combination with a yarn receiver, of a rotatable driving member situated axially of and connected directly to the yarn receiver and by which it is rotated, a winding head constructed to wind a yarn mass in layers extending transversely to the axis of rotation, and means operated by the rotary movement 55 of the driving member to cause a relative ro-

tary movement between the winding head and yarn receiver.

5. In a device of the class described, the combination with a yarn receiver, of a rotatable driving member situated axially of and 70 connected directly to the yarn receiver and by which it is rotated, a winding head constructed to wind a yarn mass under pressure in layers extending transversely to the axis of rotation, and means operated by the 75 rotary movement of the driving member to rotate the winding head at a different rate of speed than that of the yarn receiver.

6. In a device of the class described, the combination, with a yarn receiver, of a rotatable driving member situated axially of and 80 connected directly to said yarn receiver and by which it is rotated, a winding head comprising a winding plate and a yarn guide, and means operated by the rotary 85 movement of the driving member to cause relative rotary movement between the yarn receiver and winding head and to vibrate said yarn guide.

7. In a device of the class described, the 90 combination with a rotatable yarn receiver, of a rotatable driving member connected directly to said yarn receiver, a winding head constructed to wind a yarn mass in layers extending transversely to the axis of rotation, means operated by the rotary movement of said yarn receiver to cause a relative 95 rotary movement between the winding head and yarn receiver, and means to vary said relative rotary movement.

8. In a device of the class described, the combination with a rotatable yarn receiver, of a rotatable driving member connected directly to said yarn receiver, a winding head constructed to wind a yarn mass in layers extending transversely to the axis of rotation, means operated by the rotary movement of the yarn receiver to rotate the winding head at a different rate of speed than that of the 100 yarn receiver, and means to vary the relative rotary speed of the winding head and yarn receiver.

9. In a device of the class described, the combination with a yarn receiver, of a rotatable driving member connected directly 115 thereto and by which it is rotated, a winding head constructed to wind a yarn mass in layers extending transversely to the axis of rotation, means operated by the rotary movement of the driving member to cause a relative rotary movement between the winding head and yarn receiver, and means to vary such relative rotary movement.

10. In a device of the class described, the combination with a yarn receiver, of a rotatable driving member connected directly 125 thereto and by which it is rotated, a winding head constructed to wind a yarn mass in layers extending transversely to the axis of rotation, means operated by the rotary move- 130

ment of the driving member to rotate the winding head at a different rate of speed than that of the yarn receiver, and means to vary the relative rotary movement between the winding head and yarn receiver.

11. In a device of the class described, the combination with a yarn receiver and means to rotate it, of a winding head constructed to wind a yarn mass in layers extending transversely to the axis of rotation, a worm situated axially of the yarn receiver but held from longitudinal movement, a worm gear meshing with said worm and mounted to rotate about said worm as the yarn receiver rotates, and means actuated by the consequent rotation of the worm gear about its own axis to cause the winding head and yarn receiver to have a relative rotary movement.

12. In a device of the class described, the combination with a yarn receiver, of a driving member connected thereto and by which it is rotated, a winding head for winding yarn in layers extending transversely to the axis of rotation, a worm situated axially of the yarn receiver, but held from longitudinal movement, a worm gear carried by the driving member and meshing with said worm, and means actuated by the rotation of said worm gear about its own axis to produce a relative rotary movement between the winding head and yarn receiver.

13. In a device of the class described, the combination with a yarn receiver and means to rotate it, of a winding head constructed to wind a yarn mass in layers extending transversely to the axis of rotation, a worm situated axially of the yarn receiver but held from longitudinal movement, a worm gear meshing with said worm and mounted to rotate about said worm as the yarn receiver rotates, means actuated by the consequent rotation of the worm gear about its own axis to cause the winding head and yarn receiver to have a relative rotary movement, and means to rotate the worm thereby to vary the relative rotary motion of the winding head and yarn receiver.

14. In a device of the class described, the combination with a yarn receiver, of a driving member connected thereto and by which it is rotated, a winding head for winding yarn in layers extending transversely to the axis of rotation, a worm situated axially of the yarn receiver but held from longitudinal movement, a worm gear carried by the driving member and meshing with said worm, means actuated by the rotation of said worm gear about its own axis to produce a relative rotary movement between the winding head and yarn receiver, and means to rotate the worm thereby to vary the relative rotary motion of the winding head and yarn receiver.

15. In a device of the class described, the

combination with a yarn receiver, of a driving member situated axially of said yarn receiver and directly connected thereto for rotating it, a winding head for winding yarn in layers extending transversely to the axis of rotation, a shaft situated axially of the yarn receiver, gearing connecting said shaft with the driving member and winding head and operating to give the winding head a rotary movement relative to the yarn receiver. 75

16. In a device of the class described, the combination with a yarn receiver, of a driving member directly connected to said yarn receiver for rotating it, a winding head for winding yarn in layers extending transversely to the axis of rotation, a shaft situated axially of the yarn receiver, gearing connecting said shaft with the driving member and winding head and operating to give the winding head a rotary movement relative to the yarn receiver, and means to rotate the shaft thereby to vary said relative rotary movement. 80

17. In a winding apparatus, the combination with a yarn receiver and means to rotate it, of a winding head including a winding plate resting on the yarn mass as it is built up and provided with a slot inclined slightly to a radial line, a vibrating yarn guide having an elongated guide eye 85 for traversing the yarn in said slot, and means to rotate said yarn receiver and winding head relative to each other. 95

18. In a winding and twisting apparatus, the combination with a rotary driving element, of a yarn receiver situated in axial alignment with said driving element and detachably connected thereto and depending therefrom, a winding head constructed to wind a yarn mass in said yarn receiver under pressure and in layers extending transversely to the axis of rotation, a vertically-movable step bearing engaging and centering the lower end of the yarn receiver, downward movement of the step bearing 105 withdrawing it from the yarn receiver to permit the latter to be detached from the driving element, and means to lock the step bearing in its elevated position. 110

19. In a winding and twisting apparatus, 115 the combination with a rotary driving element, of a yarn receiver situated in axial alignment therewith and detachably connected thereto and depending therefrom, a winding head constructed to wind a yarn 120 mass in said yarn receiver under pressure and in layers extending transversely to the axis of rotation of the yarn receiver, means operated by the rotary movement of the driving member to cause a relative rotary 125 movement between the winding head and yarn receiver, and a step bearing movable vertically relative to the yarn receiver and adapted in its raised position to engage and center the lower end of the yarn receiver. 130

6

20. In a winding and twisting apparatus, the combination with a yarn receiver, of a driving member from which said yarn receiver depends and by which it is rotated, a winding head for winding a yarn mass in said yarn receiver, a standard or support, a step bearing slidable vertically therein and which is adapted to engage the lower end of

the yarn receiver, said step bearing having a notch, and a locking bar carried by the standard and adapted to enter said notch and lock the step bearing in its elevated position.

In testimony whereof, I have signed my name to this specification.

CHARLES W. HUBBARD.
